UNITED STATES PATENT OFFICE.

ANTON FRANK BROTH, OF KOHLER, WISCONSIN, ASSIGNOR TO KOHLER COMPANY, OF KOHLER, WISCONSIN, A CORPORATION OF WISCONSIN.

VOLTAGE REGULATOR WITH THERMOSTATIC COMPENSATOR.

Application filed June 12, 1924. Serial No. 719,601.

This invention has for its object to provide means for automatically compensating for the variation in regulation that is due to the temperature of the solenoid windings in a voltage regulator such as that disclosed in my pending application for Letters Patent for voltage regulators, Serial No. 656,384, filed August 8, 1923.

The object of such regulators is to correspondingly vary the speed of the generator with the variations in the load to maintain an approximately constant voltage.

While the invention is not confined to any particular adaptation, it is especially applicable to internal combustion engine driven farm lighting and power plants and serves to more closely proportion the fuel consumption to the actual load and maintain constant voltage.

The present invention provides an expanding and contracting thermostatic member sensitive to the variations in temperature of the voltage regulator solenoid for lengthening or shortening the connection with the spring or the speed-varying means whereby the variation in strength of the solenoid will be compensated for and the speed-varying means will remain unaffected.

With the above and other objects in view the invention consists in the voltage regulator with thermostatic compensator as herein claimed and all equivalents.

Referring to the accompanying drawings, in which like characters of reference indicate similar parts in different views,

Fig. 1 is a sectional view of a voltage regulator for generators constructed in accordance with this invention;

Fig. 2 is a diagram showing a generator circuit including the voltage regulator;

Fig. 3 is a sectional view of one of the bimetallic thermostatic disks.

In the drawings, 10 indicates a generator driven by an internal combustion engine, the throttle valve 11 of which is controlled by a solenoid having windings connected with the generator windings, as will be described. The generator as shown is of the shunt type and supplies the mains 12 containing lamps 13 or other translating devices. The shunt field winding 14 of the generator is opposed by a bucking series field winding 15, which becomes stronger as the load on the mains increases and thereby opposes a greater influence to the shunt field to

weaken the field strength. At the same time a series coil 16, also in the load circuit and strengthened by the increasing load, opposes to a greater extent the influence of a shunt or voltage coil 17 to effect a further opening movement of the throttle valve of the engine to increase the speed of the engine.

The solenoid is so constructed that the voltage coil 17 of many turns of fine wire 65 connected in parallel with the shunt field 14 and the current or series coil 16 of few turns of large wire in the load circuit together act upon the core 21 but in opposition to each other. The solenoid core is pivotally 70 connected to the shorter arm of a bell-crank lever 23, the other arm of which is connected by a link 27 with the throttle 11 so that in the extreme upper position of the core, as when the generator is not operating and the 75 coils are therefore not energized, the throttle is held in an open position, as shown in Fig. 1. The core is held in this position by a coiled spring 25 which affords a yielding resistance to the operation of the solenoid 80 core.

When the generator is started with a minimum load or no load on the service mains, the series coil 16 opposes the voltage coil 17 only slightly or not at all, and the core will be drawn to a lower position against the action of spring 25 and will move the throttle to a position partially closing the intake manifold of the engine, as shown by dotted lines in Fig. 1, so that the engine operates 85 at a minimum speed under which the generator develops the line voltage. As the load increases the generator field is weakened by the bucking series field 15, as above mentioned, and the influence of the bucking current coil or series coil 16 becomes greater, tending to neutralize the influence of the voltage coil 17 and permitting the spring 25 to lift the core and move the throttle toward its open position, thus increasing the supply 90 of fuel to the engine to increase its speed corresponding with the increase in the load.

The proportioning of the field windings of the generator and of the coils of the solenoid and of the throttle and its operating 105 means is made to compensate for a change in load by causing a change in speed without a material change in voltage developed by the generator. The weakening of the generator field by the bucking coil 15 serves to 110

2

facilitate the increasing of the speed of the engine caused at the same time by the bucking influence of the series coil 16 of the solenoid opening the throttle, and this bucking field winding exaggerates the speed variation characteristic of the generator for constant voltage conditions so that the desired object is accomplished of materially reducing fuel consumption to correspond with a 10 reduction of load.

For increased independent regulation a resistance 30 is connected in series with the shunt field winding 14 of the generator and wires 31 and 32 connect the ends of this resistance with switch contacts 33 and 34, respectively, of a resistance short circuiting switch operated by a solenoid 50 which is connected across the terminals of the generator preferably with a resistance 51 in 15 series therewith. Thus the field regulating resistance short circuit is controlled by a switch independent of the throttle controlling solenoid but sensitive to the variation in voltage developed by the generator. Being 20 independent it is not affected by the spring adjustments of the solenoid core.

By this arrangement the momentary rise in voltage when the load is suddenly reduced from full load to minimum load is prevented, the sudden weakening of the bucking current coil 16 accompanied by a slight strengthening of the voltage coil 17 being sufficient to cause the core 21 to move to the position for closing the throttle. At the 30 same time the voltage coil 50, because of such momentary rise in voltage, opens the contacts 33 and 34, thus breaking the short circuit around the regulating resistance 30 including this resistance in the shunt field 35 winding to weaken the fields and check the rise in voltage. Such tendency to abnormal voltage is only momentary and as soon as the speed of the generator has reduced to correspond with the new throttle position, 40 the normal conditions are restored, the throttle position being determined by the differential solenoid 16-17 and the field resistance short circuiting switch being permitted to close by the voltage coil 50.

As so far described the present invention is like that covered by my application for voltage regulators, Serial No. 656,334 referred to and regulation is sufficiently close for all practical purposes. However, it may, 55 under some conditions, be desirable to compensate for the variation in magnetic strength of the solenoid incident to the change in temperature thereof under operating conditions. When the solenoid coils 60 are formed as usual of copper wire having a positive temperature coefficient, the predetermined regulation voltage may be slightly exceeded by a disproportional increased opening of the throttle due to the 65 increased solenoid temperature under oper-

ating conditions. The temperature rise is not only due to the flow of current through the voltage coil 17 itself but to the heating influence of the bucking current coil 16 associated with it and carrying the load current. The increasing resistance of the voltage coil 17 results in a reduction in the current flow through it so as to diminish its value, in its tendency to close the throttle, and consequently the bucking current coil 16, aided by the spring 25, has a disproportionate influence in its tendency to open the throttle, resulting in the throttle being opened wider than it should be for maintaining the predetermined regulating voltage 75 under the then existing load conditions with an accompanying slightly excessive speed of the engine and slightly excessive voltage.

The present invention provides thermostatic means sensitive to the changes in temperature of the solenoid for compensating for the weakening of the voltage coil when it becomes hotter by automatically reducing the effective pressure of the spring on the solenoid core, thus permitting of this temperature change taking place during a given load condition without alternating the position of the throttle.

The provision for reducing the effective spring pressure on the core as the solenoid 95 becomes heated is shown in Fig. 1, wherein the core member 21 is directly pivotally connected with the arm of bell-crank 23 and the coiled spring 25 mounted on a fixed spring seat 60, which may or may not be 100 adjustable, does not bear directly against the core but bears on a plunger 61 slidably fitting in a bore of the core in bearing against a column of thermostatic elements 62. These thermostatic elements 62 are 105 preferably in the form of concavo-convex sheet metal disks of bi-metallic thermostatic metal so curved that an increase in temperature causes them to flatten and in the column they are alternately arranged so that 110 their flattening tendency is cumulative, causing an effective shortening of the column with increasing temperature. This allows the plunger 61 to move farther into the bore of the solenoid core, consequently permitting the spring to expand and reduce the spring pressure against the core. The parts are so proportioned that this relief of spring pressure compensates for the weakening of the voltage coil by the increase in temperature with the result that the position of the throttle is unaffected for a given load condition. On cooling the thermostatic disks resume their normal curvature and restore the 115 normal length of the column.

The spring 25 engages a spring seat washer or other shoulder 63 on the reduced portion of the plunger 61, which is sufficiently spaced from the head thereof to permit of the compensating movements of the plunger. 12

It is obvious that the thermostatic disks may be arranged to increase their curvature with increasing temperature or that other thermostatic elements may be employed to effect the compensation.

With this invention the predetermined voltage for the system is more closely maintained by compensating for the weakening of the voltage coil from its increase in temperature so that changes in temperature may take place without affecting the speed of the engine.

What I claim as new and desire to secure by Letters Patent is:

- 15 1. In a gas engine operated generating system, means for automatically varying the speed of the engine with the load comprising a solenoid having its winding adapted for connection with the generator winding and its core adapted for connection with the throttle, a spring acting on the core, and a thermostatic means contained in the solenoid core for varying the position of the core with respect to its spring.
- 20 2. In a gas engine operated generating system, means for automatically varying the speed of the engine with the load comprising

a solenoid having its winding adapted for connection with the generator winding and its core adapted for connection with the 30 throttle, a thermostatic element carried by the core, and a spring bearing thereon.

3. In a gas engine operated generating system, a voltage regulator comprising a solenoid having its winding adapted for 35 connection with the generator winding and its core adapted for connection with the throttle, a plunger slidably fitting in a bore of the core, a column of curved thermostatic disks contained within the bore of the core 40 and engaged by the plunger, and a spring bearing on the plunger.

4. In a gas engine operated generating system, means for automatically varying the speed of the engine with the load comprising a solenoid having its winding adapted for connection with the generator winding and its core adapted for connection with the throttle, and temperature-compensating means sensitive to the temperature of the 50 solenoid for varying the influence of the core.

In testimony whereof, I affix my signature.
ANTON FRANK BROTZ.
